CLAIM

The ornamental design for a travel bag as shown and described.

DESCRIPTION

FIG. 1 is a front, left and bottom view of a travel bag, showing my new design;

FIG. 2 is a front view thereof;

FIG. 3 is a rear view thereof;

FIG. 4 is a bottom view thereof;

FIG. 5 is a top view thereof;

FIG. 6 is a right side view thereof; and,

FIG. 7 is a left side view thereof.

The features shown in long broken lines depict environmental structure and portions of the travel bag that form no part of the claimed design. The short broken lines in FIG. 3 show stitching that is part of the claimed design. The pattern shown on the webbing extending across the front of the travel bag is part of the claimed design and indicative of the woven structure of the webbing. The dash-dot broken lines across the unclaimed carrying strap portions indicate boundary lines and do not form part of the claimed design.
